[57] CLAIM

The ornamental design for a massaging device, as shown.

DESCRIPTION

FIG. 1 is an elevation view of the new massaging device.

FIG. 2 is a side view thereof taken in the direction of arrow 2 in FIG. 1.

FIG. 3 is an end view thereof taken in the direction of arrow 3 in FIG. 1.

The other elevation, side and end views of the new massaging device are substantially the mirror image of the elevation, side and end views shown.
